UNITED STATES PATENT OFFICE.

TUVE ESBIORNSON, OF PHILADELPHIA, PENNSYLVANIA.

SQUARE.

SPECIFICATION forming part of Letters Patent No. 745,171, dated November 24, 1903.

Application filed August 14, 1902. Serial No. 119,584. (No model.)

To all whom it may concern.

Be it known that I, TUVE ESBIORNSON, a citizen of the United States, residing at Philadelphia, in the county of Philadelphia and 5 State of Pennsylvania, have invented certain new and useful Improvements in Squares, of which the following is a specification.

This invention relates to squares, and has for its object to provide a simple and efficient 10 construction whereby the size of the square may be readily reduced or enlarged as occasion may require.

With this object in view the invention consists in the novel construction and combinations of parts, which will be hereinafter fully 15 described and claimed.

In the drawings, Figure 1 is an elevation of 20 my improved square. Fig. 2 is a similar view with the extension members removed. Fig. 25 3 is a sectional detail as on the line 3 3 of Fig. 1.

1 designates my improved square, comprising 25 the usual long and short arms 2 and 4, respectively, and the extension-pieces 5, 5, which form, in effect, a continuation of the arms.

The arms 2 and 4 and the extension-pieces 5 may be constructed of sheet metal or any suitable material.

30 The arms 2 and 4 are preferably formed of one piece, as shown in the drawings.

The outer ends of the arms 2 are provided 35 with dovetail offsets 6, the respective sides of which constitute undercut projections, and the extension-pieces 5 are provided with undercut or dovetail projections 7, which are adapted to register with the offsets, and thereby securely lock the extension-pieces 5 to the arms 2.

40 In order to maintain the extension-pieces 5 in line with the arms 2 and to maintain the engagement of the dovetail projections 7 with their offsets 6, I provide slide-blocks 8. These slide-blocks are fitted to V-shaped 45 ribs 9 on the inner walls of oppositely-disposed elongated openings 10 in the meeting ends of the arms 2 and extension-pieces 5.

The opening 10 in each extension-piece 5 is sufficiently long to receive its block 8, and 50 thereby permit the withdrawal of the latter from the opening 10 in the opposing arm.

By the above-described construction it will be seen that when the blocks 8 occupy the positions shown in the drawings the extension-pieces 5 are rigidly locked to the arms 2 4 55 in line therewith and that if the blocks 8 be moved into the openings 10 in the extension-pieces 5 the blocks will be disengaged from the openings 10 in the arms 2 4, whereupon the extension-pieces may be readily removed from the square.

I claim—

1. A square comprising a pair of integral arms arranged at right angles to each other, an extension member, an undercut projection 65 and an undercut offset at the meeting ends of said member and one of said arms; said projection being adapted to register with said offset to retain said extension member in engagement with one of said arms, said arms, 70 extension member and projection being all of the same thickness and said offset extending from face to face of the square; and means for detachably maintaining said projection within said offset. 75

2. A square comprising a pair of integral arms arranged at right angles to each other, an extension member, an undercut projection and an undercut offset at the meeting ends of said member and one of said arms; said projection being adapted to register with said offset to retain said extension member in engagement with one of said arms, said arms, extension member and projection being all of the same thickness and said offset extending 80 from face to face of the square; oppositely-disposed openings in the meeting ends of said member and one of said arms, and a slide-block fitted to said openings so as to be slidably retained within the latter, one of said 85 openings being sufficiently long to permit the withdrawal of said block from the opposite opening. 90

In testimony whereof I affix my signature in presence of two witnesses.

TUVE ESBIORNSON.
